DRINKING GLASS

Edward J. Foster, Cincinnati, Ohio, assignor to
Agnes C. Foster, Cincinnati, Ohio

Application January 25, 1952, Serial No. 18,241

Term of patent 14 years

(Cl. D36—8)

To all whom it may concern:

Be it known that I, Edward J. Foster, a citizen of the United States of America, residing at Delhi Hills, Cincinnati, Hamilton County, State of Ohio, have invented a new, original, and ornamental Design for a Drinking Glass, of which the following is a specification, reference being had to the accompanying drawing, forming a part thereof.

In the drawing:

Fig. 1 is a side elevation, partially in cross-section, of a drinking glass showing my new design;

Fig. 2 is a top plan view thereof; and,
Fig. 3 is a bottom plan view thereof.

I claim:

The ornamental design for a drinking glass, as shown.
